UNITED STATES PATENT OFFICE.

EDWARD CHACE, OF WASHINGTON, DISTRICT OF COLUMBIA, ASSIGNOR OF ONE-HALF TO ANDREW J. SANFORD AND GEORGE W. SANFORD, JR., OF SAME PLACE.

GAME APPARATUS.

SPECIFICATION forming part of Letters Patent No. 544,208, dated August 6, 1895.

Application filed January 31, 1895. Serial No. 536,838. (No model.)

To all whom it may concern:

Be it known that I, EDWARD CHACE, a citizen of the United States, residing at Washington city, District of Columbia, have invented 5 new and useful Improvements in Game Apparatus, of which the following is a specification.

My invention relates to mechanical ball-games; and it consists in certain novel features and combinations in a game apparatus especially designed for the playing of a miniature game of base-ball in a manner that will substantially accord with the ordinary rules of the field game.

15 In the annexed drawings, illustrating the invention, Figure 1 is a perspective of a game apparatus constructed according to my invention. Fig. 2 is an under plan view of the game-board shown in Fig. 1. Fig. 3 is a sectional 20 detail view of one form of mechanical automatically-actuated "batter" and the portion of the board to which it is attached. Fig. 4 is a vertical section of a portion of a game-board provided with a self-setting and automatically-actuated batter. Fig. 5 is a perspective of a base-ball game-board illustrating modified devices for controlling and releasing the balls, marbles, or rolling objects that are to represent the batting team or side. 25 Fig. 6 is a plan of the under side of the game-board shown in Fig. 5. Fig. 7 is a detail view of a portion of a lever mechanism for controlling a movable guard device to retain or release one of the balls or marbles comprised 30 in the batting-team.

Referring to the drawings, the numeral 1 designates a rectangular frame supporting a game-board 2, arranged to represent the infield or "diamond" of a base-ball ground.

40 In the preferred form of construction shown in Figs. 1 and 2 a series of tilting troughs or ways 3, 4, 5, and 6 are pivotally attached to the outer sides of the game-board frame 1 in such manner that when at rest each trough 45 will normally incline rearward or from a farther or following "base" to the one that immediately precedes it. Thus the tilting trough 3 is normally inclined from the point "F. B.," designating the first base, to the point "H. B.," which may designate the home base in the miniature and mechanical game of base-

ball. In like manner the next tilting trough 4 is normally inclined from the second base, "S. B.," to the first base; the tilting trough 5 is normally inclined from the third base, "T. B.," to the second base, and the last tilting trough 6 is normally inclined from the home-base to the third base. These tilting troughs constitute the base line or course and are each constructed to serve as a runway for a number 60 of balls, marbles, or rolling objects, such as 7, which are to form part of the game apparatus and may be used to represent the batting and running team. The normally-rearward inclination of each tilting trough serves 65 to retain a ball, marble, or other spherical object thereon in a position of rest at the base where it belongs until an opportunity offers for making a run.

To that end of each tilting trough or way 70 which is lowest when the trough is in its normally-rearward inclined position may be attached one or more stationary stops or guards 8 projecting above the end and a portion of the outer side of the trough in such manner 75 as to retain a ball or marble 7 thereon until it is time for it to make a run, as hereinafter explained. This stop or guard 8 may be formed on each trough by attaching an angular piece of metal thereto in such manner 80 that it will project above the end and a portion of the outer side of the trough, as shown, or the said guard may be integral with the trough and be formed thereon in any suitable and convenient manner. The stop or guard 85 8 does not project above the inner side of a trough, because a passage must be afforded for a ball or marble to roll from one trough onto the next succeeding trough when the preceding one is properly operated, so as to cause 90 it to be tilted forward and thereby inclined in the required direction.

As before observed, the several tilting troughs or ways are normally inclined rearward or from a farther base toward one next 95 preceding. Any suitable mechanism may be provided for operating any particular trough separately, or several troughs simultaneously, in such manner as to cause a trough or troughs to be tilted or inclined forward, and thereby 100 cause one or more balls or marbles to make a run along a portion or the whole of the base-

line or course. If only one trough is operated at a time so as to be tilted forward, the guard or guards 8 on the lower end of the next normally-rearward inclined trough will arrest 5 the running ball or marble at the required base on the field or course. When, however, two immediately-adjacent troughs are simultaneously operated, the ball or marble running on the rearward trough cannot pass at 10 once onto the one next succeeding, and some means must therefore be provided to prevent it from running off the temporarily-depressed forward end of the trough or way along which it has just traveled and to retain it at that 15 point in readiness to pass at once to the required base as soon as the next succeeding trough is allowed to resume its normally-rearward inclination. This may be accomplished by providing a depending stop or guard 9, Fig. 20 1, on the inner side of a trough end, at a right angle to its angular guard 8, to occupy a working position immediately across the temporarily-depressed forward end of the preceding trough.

25 For the purpose of operating the tilting troughs or runways 3, 4, 5, and 6 I prefer to provide a series of pivotally-supported finger-keys 3^a, 4^a, 5^a, and 6^a, Figs. 1 and 2, of varying lengths and arranged to project from one 30 side of the game-board frame in such proximity to each other that they can be conveniently manipulated either separately or simultaneously, as may be required. These finger-keys may project through slots 10 formed in 35 one side of the frame 1 at convenient points below the highest portion of one of the normally-rearward inclined tilting troughs.

Beneath the game-board is a rod or shaft 11, 40 Fig. 2, on which the several keys are fulcrumed. The key 3^a is directly connected by short links 12, Fig. 1, to the under side of the normally-highest end portion of the trough 3, so that by depressing the key the trough will 45 be tilted forward and permit a ball or marble to roll thereon from the home base to the first base, at which point, if only the trough 3 has been operated, the ball or marble will roll at once onto and remain on the lower end of the normally-rearward inclined trough 4 until 50 that trough is tilted forward by depressing its finger-key. The key 4^a of the tilting trough 4 is arranged to bear upward at its inner end upon a rod or lever 13, Fig. 2, extended at right angles to the key and having one end 55 pivoted or hinged at 14 to one side of the frame and its other end passed through a slot 15 in the opposite side of the frame and connected to the trough 4 at a suitable point. The finger-key 5^a has a lever-extension 16 that is carried 60 across the under side of the game-board and through a slot 17, Fig. 2, in one side of the frame, to connect with the tilting trough 5 at a proper point for effecting its required operation. At its inner end the finger-key 6^a 65 bears on or may connect with a rod or lever 18, Fig. 2, one end of which is hinged or pivotally connected at 19 to one side of the frame and

the other end is passed through a slot 20 in the opposite side of the frame and connected to the tilting trough 6 at an appropriate point. 70 Each tilting trough 3, 4, 5, and 6 has a fulcrum 21 arranged nearer one end than the other, and these several finger-keys are each connected with a trough at such point with relation to the trough-fulcrum as will best provide 75 for the required operation of the troughs either separately or two or more at a time.

On the top of the game-board, preferably adjacent to the home base, is hinged or pivotally supported a vertically-swinging batter 22, 80 which consists of a bar that is normally held in an erect position. This batter is so arranged that upon receiving the impact of a ball or marble shot or projected against its front face or side it will immediately be released 85 from its erect position and caused to react on the ball or marble in such manner as to quickly deliver a blow that will throw the said ball or marble outward from the game-board and onto the floor or table, unless it can be 90 caught "on the fly" by the player who projected it against the batter.

In Figs. 1, 3, and 5 I have shown the mechanical batter 22 as connected to the top of the game-board by means of a hinge 23 so arranged as to permit the batter to swing sharply forward when released. This hinged batter has secured to its lower end a bent arm 24, extended downward through a slot 25 in the game-board and connected to one end of a 100 preferably spirally-coiled spring 26, the other end of which is fastened to the under side of the game-board.

In slots 27 and 28 of the game-board is arranged a movable segmental rack 29, that is 105 adapted to interlock with and hold the batter 22 in an erect or set position. The rear end portion of the segmental rack 29 is pivoted in or immediately below the slot 27, and the forward end of the rack works in the slot 110 28, through which it may be raised and lowered. In the top of the rack 29 is a notch 30, adapted to engage and become locked with a pin 31, Fig. 3, mounted in a slot 32, with which the batter 22 is provided and through which 115 the segmental rack 29 is extended. When the batter 22 is set in an erect position and the rack 29 raised for its notch 30 to engage the pin 31, the tension to which the spring 26 is thus subjected will cause it to hold the batter and its locking-rack in firm engagement. The batter 22 will remain set or erect until it receives a slight rearward impulse, as by the impact of a ball or marble thrown, shot, or otherwise projected against its forward 120 face, which will be sufficient to disengage the pin 31 from the notch 30 and allow the forward end portion of the segmental rack to drop at the same instant that the batter will be swung sharply forward by the contraction 125 of its spring.

In this miniature game of base-ball there may be two or more players and the rules of the game may correspond as nearly as possi-

ble with the usage of the field game. One player or one side will take charge of the balls or marbles that are to represent the movements of the batting and running team.

5 Another player or side will take charge of the ball or marble that is to be batted. If desired the balls or marbles may have distinguishing colors or numbers, though this is not essential. At the beginning of the game

10 the batter 22 will be set in its erect position and one of the balls or marbles of the batting and running team will be placed in the lower or home-base end of the tilting trough 3, all the said troughs being at rest in normally-rearward inclined positions. The player who has the ball or marble to be batted, and who may represent the "pitcher," will toss or shoot the ball or marble in proper direction to strike on the face of the mechanical batter 22, and this, when hit, will yield slightly to release the pin or catch 31 from the notched rack 29, that instantly falls while the batter 22 quickly rebounds, under the action of its spring, and is swung forward with such force

15 as to drive the ball outward onto the floor or table on which the game-board may rest. As soon as the ball is batted the player in charge of the running team of balls or marbles will depress the key 3^a to put in motion the ball or marble supported by the trough or way 3 and allow it to roll to first base and onto the depressed end of the trough 4 at that point; but in the meantime if the pitcher, or one of his side, can catch the batted ball or pick it up and place it on first base before the running ball or marble on the trough or way 3 gets to that base the latter ball or marble will be put out. On resetting the mechanical batter 22 and repeating its

20 operation by impact of a ball thereon the keys 3^a and 4^a may be depressed, either separately or simultaneously, to cause the running of a ball or marble from home base to first base and from first base to second base,

25 and so on, if there is time for those runs before the batted ball can be caught and carried to the destined base of one of the running balls or marbles. So, also, the keys 5^a and 6^a may be depressed, either separately or

30 simultaneously, to cause the rolling of balls or marbles farther along the course. In this manner the play may be continued by repeated resetting of the mechanical batter and a proper manipulation of one or more of the

35 keys, either separately or simultaneously, according to the progress of the game. A skillful manipulation of the keys will permit the operation of the tilting troughs or ways in such manner that a ball, marble, or other

40 rolling object thereon may be permitted to proceed only part way toward the desired base and then be quickly returned to the base just passed, if the exigencies of the game should require such movements in order to

45 prevent a ball or marble from being put out while on a run. When three of the marbles in the running team have been put out, the

other side, or the other one of two opposing players, may take charge of the team and the game may proceed in accordance with any 70 suitable rules approximating those followed in the regular game.

As shown in Fig. 4, the mechanical and vertically-swinging batter 22 may be mounted on trunnions 33, supported in bearings 34, 75 above and on opposite sides of a slot 35 formed in the top of the game-board. A weight 36 on the lower end of this batter will serve to carry it to a normally-erect position, and thereby effect its automatic resetting after 80 the batting of a ball. Below the slot 35 is mounted a rotary shaft or spindle 37, having a series of radial arms 38, adapted to project in turn through the slot 35 a sufficient distance to be caused to strike against the 85 weighted lower end of the batter in such manner as to force it backward and thereby throw the upper end of the batter forcibly forward in batting the ball. A coiled spring 39, connected with the shaft or spindle 37, may furnish the motive power for rotating said shaft. A stop-lever 40, Fig. 4, is fulcrumed at its lower end and carries a stop lug or shoulder 41, adapted to engage over one of the horizontally-extended arms 38, and thereby arrest the rotation of the shaft to which the arms 38 are attached. The upper end of the stop-lever 40 is connected with the lower end of the batter 22 by a rod 42, and a light spring 43 is arranged adjacent to said lever in such 90 position as to aid in restoring engagement of the stop 41 with one of the arms 38 and arrest the oscillation of the batter after it has rebounded against the impact of a ball.

Instead of having the base-line or course 105 composed of a series of tilting troughs or ways, I may provide runways or troughs 44, Fig. 5, that communicate with each other and are permanently inclined in proper direction and in a spiral manner to cause a ball or marble 110 to roll from one base to another. As a means for controlling the release of balls or marbles placed at the higher end of each permanently-inclined trough or way 44, I provide in each trough or runway, near its upper end, an adjustable guard device that may conveniently take the form of a vertically-movable pin or series of pins 45, respectively operated from one of the finger-keys 3^a, 4^a, 5^a, or 6^a, herein-before described. These keys may be fulcrumed on a rod or bar 11^a, Fig. 6, substantially as before. The key 3^a will carry near its outer end the guard or vertically-movable pin 45 for retaining and releasing a ball or marble placed on the higher end portion of 115 the spirally-inclined runway 44 adjacent to home base. The key 4^a when depressed will bear down on a lever 46, Fig. 6, having one end fulcrumed at 47 and its other end carrying the guard or pin for controlling release 120 of the ball or marble at first base. The key 5^a may be arranged to actuate a lever 48 fulcrumed at 49 intermediate its ends and connected at one end with the guard or pin for

retaining and releasing the ball or marble at second base. In like manner the key 6^a will control a lever 50, Figs. 6 and 7, fulcrumed at 51 and carrying the guard or pin for arresting 5 and releasing a ball or marble at third base.

It will be readily understood that the several finger-keys may be depressed, either separately or any two or more simultaneously, according to the requirements of the game at 10 different stages of its progress, as hereinbefore explained. At the angles or turning-points of the spirally-inclined runway 44 there may be placed suitable fixed guards 52 to prevent the rolling balls or marbles from leaving the 15 course or base-line.

The same kind of ball-game can be played with both forms of game-board illustrated, which are alike in all essential particulars, and any appropriate rules may be adopted 20 for governing the manner of conducting a game.

What I claim as my invention is—

1. A game apparatus comprising a board or surface representing the infield of a base- 25 ball ground, a series of inclined ways constituting a base line or course for rolling objects, a normally erect and vertically swinging batter mounted on the said board adjacent to home base, and means for locking the 30 batter in an erect position until released by the impact of a ball thereon, substantially as described.

2. A game apparatus comprising a board

having thereon positions representing the bases of a base-ball ground, a mechanical and 35 automatically actuated batter pivotally supported on the upper side of the board, mechanism for holding the batter in a normally erect position until released by the impact of a ball or other object, spring mechanism for 40 causing the batter to rebound forcibly and thereby drive the ball, and tilting ways constituting a base-line or course from base to base and over which rolling objects may be caused to pass either forward or back between 45 the bases, substantially as described.

3. A game apparatus comprising a board representing the infield of a base-ball ground, an automatically actuated and rebounding batter supported on the said board in position 50 to receive and respond to the impact of a ball, marble or other suitable object, tilting ways constituting a base line or course over which rolling objects may be caused to pass either forward or back between the several bases of 55 the infield, and mechanism for operating said tilting ways to cause them to incline either forward or backward, substantially as described.

In testimony whereof I have hereunto set 60 my hand in presence of two subscribing witnesses.

EDWARD CHACE.
